ICE SAWING MACHINE

John Duray, Minto, N. Dak.

Application October 17, 1938, Serial No. 235,495

3 Claims. (Cl. 262—31)

My invention relates to improvements in ice sawing machines and has as one of the principal objects thereof the provision of a machine of the above described character so constructed and arranged as to be operable over an ice field for cutting said ice in such a way that it may be divided up into cakes or blocks which can be more readily handled and packed.

Another object of my invention is to provide a machine of the character described which is simple in construction, durable in use, efficient in operation and economical in manufacture.

Other objects and advantages will be apparent from the following description, appended claims and annexed drawings.

Referring to the drawings wherein like reference characters designate like parts throughout the several views:

- 20 Figure 1 is a side elevation of my invention.
 Figure 2 is a top plan view thereof.
 Figure 3 is a rear elevation of my invention.
 Figure 4 is a detail sectional view taken on the line 4—4 of Figure 1.

25 Figure 5 is a detail perspective view of the cross head.

In practicing my invention I provide a sled 5 comprising a pair of runners 6 secured in spaced relation by cross bars 7, the ends of the latter being secured in spaced recesses formed in the top faces of said runners. A longitudinally extending bed 8 is secured on the upper faces of the cross bars 7 between the runners 6 and is provided, adjacent the front end of the sled, with a pair of longitudinally extending spaced guides 9 on which is slidably mounted a base 10 of an engine 11 of an ordinary construction and equipped with the usual drive shaft on which is mounted for rotation therewith a drive pulley 12.

Secured on the top faces of the runners 6, adjacent the rear end of the sled, are a pair of spaced uprights 13, the upper ends of the latter being provided with bearings 14 through which is journaled a transversely extending shaft 15. Fixed on the shaft 15, between the bearings 14, is a driven pulley 16 and trained over the pulleys 12 and 16 is a drive belt 17 whereby said shaft 15 is driven by the engine 11. Mounted on the cross bars 7, adjacent the front end of the sled, is a plate 18 provided with teeth for engagement with a spring pressed pawl mounted on a lever 19 pivoted to the plate. The lever 19 is pivotally connected to the engine 11 by means of a connecting rod 20 whereby upon adjustment of the lever relative to the plate, through the medium of the pawl and teeth, said engine is moved rela-

tive to the guides 9 to effect tightening or loosening of the belt about the pulleys 12 and 16 to rotate or preclude rotation of the shaft 15 respectively as desired.

The front end of the sled is provided with a pair of handles 21 whereby said sled may be pulled over the surface of ice 22 to effect cutting thereof in a manner hereinafter more fully set forth.

Subjacent the upper end thereof, one of the uprights 13 has pivoted thereto on the outer side face thereof the upper end of a cross head frame 23. The cross head frame 23 is provided subjacent the upper end thereof with a grooved guide member 24 in which is slidably mounted offset portions 25 of a head 26. The guide member 24 has secured thereto, by means of screws, detachable plates 27 overlying the portions 25 of the head whereby to maintain the latter in reciprocal relation with the frame.

20 The upper end of a saw blade 28 is pivoted to the head 26, adjacent the upper end thereof, by means of a pivot pin 29 threaded in said head and said saw blade extends an appreciable distance subjacent the adjacent runner 6 for engagement with the ice whereby to effect cutting of the latter upon reciprocation of the saw blade and forward movement of the sled. Mounted on the outer end of the shaft 15, adjacent the frame 23, is an eccentric disk 30 having pivoted thereto 30 the upper end of an eccentric bar 31, the lower end of which is pivotally connected to the pivot pin 29 whereby to effect reciprocation of the saw blade relative to the frame 23 upon rotation of the shaft 15.

35 A U-shaped guide 32 is attached to the head 26 below the pivot pin 29 and limits the forward pivoting movement of the saw blade and tends to hold said blade against lateral outward movement with relation to the frame. A keeper 33 is 40 secured to the outer face of the runner adjacent the saw blade whereby said saw blade may be disposed thereon when not in use as clearly illustrated in dotted lines in Figure 1.

The movement of the frame 23 relative to the 45 adjacent upright is limited by a pin 34 carried by said upright and operable in a slot 35 formed in the frame. The frame is normally held in upright position by a spring 36 which is secured to the lower end of the frame and to the adjacent 50 runner.

From the foregoing it will be readily understood that the sled may be positioned on the surface of ice and the saw blade inserted through said ice to effect cutting of the ice upon operation 55

of the motor and propelling of the sled as heretofore set forth. It is to be distinctly understood that various changes and modifications may be resorted to in the construction and arrangement of my invention without departing from the spirit thereof or scope of the appended claims.

What I claim is:

- 5 1. A device of the character described, comprising, a sled equipped with a pair of uprights, a shaft mounted on said uprights, a cross head frame pivotally mounted on one of said uprights, a cross head slidably mounted in said frame, a saw blade pivoted to said cross head for reciprocation therewith and extending an appreciable distance below said sled for engagement with a body of ice to effect cutting of the latter upon reciprocation of said blade and forward movement of said sled, a guide member carried by said head and receiving said blade for maintaining the latter in ice cutting position during reciprocation of the blade in said ice cutting position, means connecting said shaft to said cross head for reciprocating the latter, and an engine mounted on said sled and connected to said shaft for rotating the latter.
- 10 2. A device of the character described, comprising, a sled equipped with a pair of uprights, a shaft mounted on said uprights, a cross head frame pivotally mounted on one of said uprights, a cross head slidably mounted in said frame, a saw blade pivoted to said cross head for reciprocation therewith and extending an appreciable distance below said sled for engagement with a body of ice to effect cutting of the latter upon reciprocation of said blade and forward movement of said sled, a guide member carried by said head and receiving said blade for maintaining the latter in ice cutting position during reciprocation of the blade in said ice cutting position, means connecting said shaft to said cross head for reciprocating the latter, and a spring connecting said sled to said frame for normally maintaining the latter in an upright position relative to said uprights and coacting with said guide member for yieldably maintaining said saw blade in engagement with said ice.
- 15 3. A device of the character described, comprising, a sled equipped with a pair of uprights, a shaft mounted on said uprights, a cross head frame pivotally mounted on one of said uprights, a cross head slidably mounted in said frame, a saw blade pivoted to said cross head for reciprocation therewith and extending an appreciable distance below said sled for engagement with a body of ice to effect cutting of the latter upon reciprocation of said blade and forward movement of said sled, a guide member carried by said head and receiving said blade for maintaining the latter in ice cutting position during reciprocation of the blade in said ice cutting position, means connecting said shaft to said cross head for reciprocating the latter, and an engine mounted on said sled and connected to said shaft for rotating the latter, and a spring connecting said sled to said frame for normally maintaining the latter in an upright position relative to said uprights and coacting with said guide member for yieldably maintaining said saw blade in engagement with said ice.
- 20 4. A device of the character described, comprising, a sled equipped with a pair of uprights, a shaft mounted on said uprights, a cross head frame pivotally mounted on one of said uprights, a cross head slidably mounted in said frame, a saw blade pivoted to said cross head for reciprocation therewith and extending an appreciable distance below said sled for engagement with a body of ice to effect cutting of the latter upon reciprocation of said blade and forward movement of said sled, a guide member carried by said head and receiving said blade for maintaining the latter in ice cutting position during reciprocation of the blade in said ice cutting position, means connecting said shaft to said cross head for reciprocating the latter, and an engine mounted on said sled and connected to said shaft for rotating the latter, and a spring connecting said sled to said frame for normally maintaining the latter in an upright position relative to said uprights and coacting with said guide member for yieldably maintaining said saw blade in engagement with said ice.
- 25 5. A device of the character described, comprising, a sled equipped with a pair of uprights, a shaft mounted on said uprights, a cross head frame pivotally mounted on one of said uprights, a cross head slidably mounted in said frame, a saw blade pivoted to said cross head for reciprocation therewith and extending an appreciable distance below said sled for engagement with a body of ice to effect cutting of the latter upon reciprocation of said blade and forward movement of said sled, a guide member carried by said head and receiving said blade for maintaining the latter in ice cutting position during reciprocation of the blade in said ice cutting position, means connecting said shaft to said cross head for reciprocating the latter, and an engine mounted on said sled and connected to said shaft for rotating the latter, and a spring connecting said sled to said frame for normally maintaining the latter in an upright position relative to said uprights and coacting with said guide member for yieldably maintaining said saw blade in engagement with said ice.
- 30 6. A device of the character described, comprising, a sled equipped with a pair of uprights, a shaft mounted on said uprights, a cross head frame pivotally mounted on one of said uprights, a cross head slidably mounted in said frame, a saw blade pivoted to said cross head for reciprocation therewith and extending an appreciable distance below said sled for engagement with a body of ice to effect cutting of the latter upon reciprocation of said blade and forward movement of said sled, a guide member carried by said head and receiving said blade for maintaining the latter in ice cutting position during reciprocation of the blade in said ice cutting position, means connecting said shaft to said cross head for reciprocating the latter, and an engine mounted on said sled and connected to said shaft for rotating the latter, and a spring connecting said sled to said frame for normally maintaining the latter in an upright position relative to said uprights and coacting with said guide member for yieldably maintaining said saw blade in engagement with said ice.
- 35 7. A device of the character described, comprising, a sled equipped with a pair of uprights, a shaft mounted on said uprights, a cross head frame pivotally mounted on one of said uprights, a cross head slidably mounted in said frame, a saw blade pivoted to said cross head for reciprocation therewith and extending an appreciable distance below said sled for engagement with a body of ice to effect cutting of the latter upon reciprocation of said blade and forward movement of said sled, a guide member carried by said head and receiving said blade for maintaining the latter in ice cutting position during reciprocation of the blade in said ice cutting position, means connecting said shaft to said cross head for reciprocating the latter, and an engine mounted on said sled and connected to said shaft for rotating the latter, and a spring connecting said sled to said frame for normally maintaining the latter in an upright position relative to said uprights and coacting with said guide member for yieldably maintaining said saw blade in engagement with said ice.

JOHN DURAY. 35
